UNITED STATES PATENT OFFICE.

ALLEN A. VAN ORSDALE AND JOHN B. LINN, OF PHILADELPHIA, PENNSYLVANIA.

DESIGN FOR A LUBRICATOR.

58,169.

Specification for Design.

Patented June 14, 1921.

Application filed September 25, 1920. Serial No. 412,880. Term of patent 3½ years.

To all whom it may concern:

Be it known that we, ALLEN A. VAN ORSDALE and JOHN B. LINN, citizens of the United States, residing at Philadelphia, in the county of Philadelphia and State of Pennsylvania, have invented a new, original, and ornamental Design for a Lubricator, of which the following is a specification, reference being had to the accompanying drawing, forming a part thereof.

Figure 1 is an elevation of the lubricator, and

Fig. 2 is a plan of the same.

We claim:

The ornamental design for a lubricator as shown.

ALLEN A. VAN ORSDALE.
JOHN B. LINN.
